KNITTING MACHINE YARN CARRIER BAR
CONTROLFred Autem, Wyomissing, Pa., assignor to Textile
Machine Works, Wyomissing, Pa., a corporation
of Pennsylvania

Application April 13, 1938, Serial No. 201,669

19 Claims. (Cl. 66—127)

This invention relates to the actuation and control of yarn carrier mechanisms for knitting machines capable of operation in recurrent sequence and otherwise, and particularly to means for automatically operating the yarn selector mechanisms and friction boxes in full fashioned knitting machines.

In full fashioned knitting machines, mechanisms have been developed for laying yarns of the same color and kind, but brought from different cones or supplies, in recurrent sequence, such as the now well known three-carrier attachments, whereby three yarns, instead of one, are laid in repeated succession to avoid rings or shadows. This principle, operating on a law of averages, depends for its results on the unlikelihood of lengths of any one of the three yarns of irregular diameter being laid immediately next to similar lengths in either of the other two yarns; these lengths being of irregular diameter occurring occasionally along silk threads.

The multi-carrier fabric has been produced by mechanism whereby the carrier operation is effected automatically, but wherein the operations for rendering the mechanism active and inactive were manually effected. Means also has been devised whereby a single friction box carrying one of the aforementioned three-carrier selectors may be manually or automatically changed from its three-carrier operation to the operation of a single carrier of the sequence. Thus, a three-carrier attachment, operating through full strokes in the leg area of a stocking blank, could be manipulated to lay one of the three yarns through short strokes, as in the reinforced heel area of a stocking.

These devices are of various designs, but they each require a special and relatively heavy, friction box which, although in certain cases it would be better to avoid its use as an actuating means for effecting the laying of single short course yarns, is, and has been, generally used as such, because of the desirability, in certain instances, of conveniently establishing an operative connection with as many carriers as possible.

The use of the above-mentioned special three-carrier friction boxes for operating the three carriers in sequence, and one of the three carriers alone, has been general, but no means, so far as I am aware, has ever been suggested for automatically throwing the three-carrier selector into and out of operation, for automatically connecting the special box to, and releasing it from, the friction rod, for operating a single carrier other than one of the sequential carriers, or for com-

bining such operations with other operations, such as the aforementioned operation of automatically changing the device back and forth between the sequential, or three-carrier operation, and other carrier operation such as the single-carrier operation mentioned. The operation of such a comparatively large and heavy special friction box, in the short stroke single yarn areas of the heel of a stocking blank, generates larger amounts of heat and wear, from the greater movements of the friction rod through the box at the ends of the short strokes, compared to the heat and wear of a smaller standard single carrier box.

It is an object of this invention to increase the flexibility, and choice, of control over the yarn carriers and friction boxes of full fashioned knitting machines, whereby to enable such machines not only to be operated as fully and effectively as they have ever heretofore been operated, but also to provide added features materially enhancing the desirability and usefulness thereof.

Another object of the invention is to provide a feature whereby, in certain instances of high-speed production, the three-carrier or special friction box of a full fashioned knitting machine may be rested, or relieved of heating and wear, during the knitting of areas, such as the heel tabs of a leg blank.

Another object of the invention is to provide a multiple-carrier attachment which may be automatically controlled as above set forth, between totally inactive condition and sequential-carrier operation.

Another object of the invention is to provide an attachment of the above-indicated character which may be automatically operated between sequential-carrier operation and other carrier operation, such as the operation of a single carrier of the sequence, or a carrier not of the sequence.

A further object of the invention is to provide an attachment of the above-indicated character which may automatically control a combination or sequence of the above-mentioned actions, and be operated in cooperation with the automatic operation of the friction box, between active and inactive positions.

With these and other objects in view, which will become apparent from the following detailed description of the illustrative embodiments of the invention shown in the accompanying drawings, the invention resides in the novel elements, features of construction and arrangement of parts in cooperative relationship, as hereinafter more particularly pointed out in the claims.

In the drawings:

Figure 1 is a top plan view, parts being omitted and intermediate sections being broken away to shorten the figure, of a multi-section straight 5 knitting machine embodying the invention, and adapted to produce full fashioned stocking blanks;

Fig. 2 is a view taken cross sectionally of the machine of Fig. 1, slightly enlarged thereover;

10 Fig. 3 is a further enlarged detail view of a three-carrier attachment and other parts as viewed generally in the direction of an arrow C of Fig. 2, certain parts being in elevation, others in section, and others being broken away or 15 omitted;

45 Fig. 16 is a view of certain of the parts shown at the upper portion of Fig. 15, but in different positions;

Fig. 17 is a sectional view taken substantially along the line 17—17 of Fig. 15;

Fig. 18 is a detail view, cross sectionally of a control shaft of the machine, showing certain 50 cams on the shaft and followers for the cams;

Fig. 19 is a cross sectional view taken substantially along the line 19—19 of Fig. 3;

Fig. 20 is similar to Fig. 19, showing the parts thereof in different positions;

55 Fig. 21 is a sectional view taken substantially along the line 21—21 of Fig. 19;

Fig. 22 is a view taken substantially along the line 22—22 of Fig. 3;

Fig. 23 is a sectional view taken substantially 60 along the line 23—23 of Fig. 22;

Fig. 24 shows parts as viewed generally in the direction of an arrow F of Fig. 6;

Fig. 25 is a view taken substantially along the line 25—25 of Fig. 7;

65 Fig. 26 is a view taken substantially along the line 26—26 of Fig. 3;

Fig. 27 is a sectional view taken substantially along the line 27—27 of Fig. 3;

70 Fig. 28 is a sectional view taken substantially along the line 28—28 of Fig. 6;

Fig. 29 is a diagram of the leg blank of a full fashioned stocking, together with pattern chains, as developed or opened out along straight lines in side elevation from the normal closed loop 75 shape thereof, indicating the positions along the

blank at which certain operations are effected by the chain links;

Figs. 30, 31, 32, 33, 34 and 35 are a progression of diagrammatic views illustrating the manner in which three carrier rods are operated in recurrent sequence to produce knitted areas of the "ringless" type;

Fig. 36 is a view similar to one of Figs. 30—35 showing how only one carrier rod is operated by the three-carrier attachment at certain times, 10 as in laying the yarn of the stocking welt;

Fig. 37 is a view of parts of a modified form of the invention corresponding to the structure of Fig. 3; and

Fig. 38 is a view corresponding to Fig. 6, of the 15 modified form of the invention of Fig. 37.

In the drawings and description, only those parts necessary to a complete understanding of the invention have been set forth; further information as to the construction and operation 20 of other elements not herein specifically pointed out, but which are usual and well known, being available in the pamphlet entitled "Full Fashioned Knitting Machines," copyright 1920, in the "Reading" Full Fashioned Knitting Machine 25 Catalogues, copyright 1929 and 1935, published by the Textile Machine Works, Reading, Penna., and in a pamphlet entitled "Knitting Machine Lectures," published in 1935 by the Wyomissing Polytechnic Institute, Wyomissing, Pennsylvania. 30

Reference may also be had to Patent No. 2,101,048 entitled "Uninterrupted knitting of shaped fabrics," and issued December 7, 1937, to Alfred E. Ischinger.

Machine frame

35

The machine frame comprises transverse end and center frames, and longitudinal members mounted on these frames, such as a front beam, a back beam, a front bed and a center bed; these 40 parts being similar to corresponding members heretofore employed in full fashioned stocking and other straight knitting machines, except as modified as to bearings and other supporting parts for the operating mechanisms which are 45 new to this invention.

Referring to the drawings, the machine of Figs. 1—36 is of the multi-section type comprising, as better seen in Figs. 1 and 2, transverse end frames 12, and transverse center frames 13, joined by a front beam 14, a back beam 17, and a center bed 18, which cooperate with a front bed 19 extending only between the center frames 13 to form a base upon which the operating parts of the machine are supported. Between each pair of the center frames 13, there is a knitting mechanism for simultaneously knitting two stocking blanks.

Main drive mechanism

A power unit for driving the operating parts of the machine, shown in the above-mentioned catalogues, is also similar to the power units of previous machines of the type producing fashioned knitted fabrics, including an electric motor on the machine frame at the rear of the machine, connected through sprocket wheels and a chain to a hand wheel shaft and, through a clutch and further sprocket wheels and a chain to a drive shaft, from which a coulier motion mechanism derives its motion. This power unit drives, in this instance, a cam shaft 22, a friction rod 23 and a slurcock box connecting rod 24.

Loop forming mechanism

In knitting a fabric, such as a full fashioned 75

stocking blank, after the yarns are laid in lengths ready for forming into loops, the usual loop forming parts, such as needles, sinkers, dividers and knockover bits, which are the parts directly engaging the yarn, are operated similarly to the manner in which such parts have heretofore been operated.

Loop forming mechanism (Figs. 2 and 4) comprises needles 32, two banks or sets of which are disposed between each pair of adjacent center frames 13. The needles of each bank are held, by clamps 33, to a needle bar 34, which is pivotally connected by a bracket 37 fixed thereto, and a pin 38, to a lifting arm 39 on a needle bar lifting shaft 42, on which is also mounted an arm 43 carrying a follower roller 44 on a shaft 47. The arm 43 is connected, by a spring 48, to a bracket 49 on the back beam 17. The follower 44 cooperates with cams, including a cam 52, on the cam shaft 22.

Forward and rearward movements of the needles are effected by a fork 53 fixed to the needle bar 34, and pivotally connected to a lever 54 having a notch 57 for resting the lever 54 on a pin 58 projecting from the side of a presser lever 59. The latter is carried by a presser shaft 62, and carries a follower roller 63 for cooperation with cams, including a cam 67, on the cam shaft 22. The presser lever 59 is connected, by a spring 72, to a bracket 73 on the back beam 17 for biasing the follower 63 toward its cam.

By lifting the lever 54 to remove the notch 57 from the pin 58, the needles may be moved from the operative position shown to an inoperative position in which a notch 74 is placed over the pin 58, and which is a position of the needles forward of the sinkers and dividers, for repair work, such as the replacement of needles. The lever 54 also has a shoulder 77 for cooperation with the pin 58 to hold the needle bar in an intermediate position.

A sinker head assembly comprises a sinker head 82, sinkers 83 and dividers 84 which are thin sheet steel elements disposed alternately in close side-by-side relation, and a verge plate or stop 87 for the sinkers.

The sinkers 83 are moved forwardly by jacks 88 which are slurred forwardly by a slur cam 89 secured to a cock box 92 mounted on a guide rail 93 for slidable movement transversely to the sinkers and dividers. The cock box 92 is secured to the connecting bar 24 and is reciprocated, parallel to the front of the machine, by the coulier motion mechanism in a usual manner.

The dividers 84 are moved forwardly and backwardly by a catch bar 94, which receives its movement from cams including a cam 97 on the cam shaft 22, through a linkage comprising a cam follower 98, a back catch lever 99, and a vertical shifting lever 102 mounted on a shaft 103, and a horizontal lever 104. A spring 105, connected between a hook extension 106 of the lever 99 and a bracket arm 110 on the front beam 14, biases the follower 98 against the cam 97.

The sinkers 83 are engaged and disengaged by the catch bar 94, by means of a front catch bar linkage comprising cams, including a cam 107, on the cam shaft 22, a cam follower 108, a front catch lever 109, and a link 112 secured to a front catch shaft 113, a vertical lever 114, and a horizontal link 117.

As the yarn is laid to the needles 32, the sinkers 83 are slurred forwardly by the jacks 88 and the slur cam 89, in spaced relation to the yarn carriers, to sink the yarn between alternate pairs of

needles. The dividers 84 are then brought forward by the catch bar 94 and its back cam linkage to complete the formation of the loops in the usual manner. Retraction, and further advancement of the sinkers 83 with the dividers 84 are accomplished by the catch bar 94, which is lowered by the front catch bar cam 107, and associated cam linkage, to engage the backs of the sinkers. Knockover bits 118 cooperate with the sinkers, dividers and needles to hold several adjacent previously knitted courses in position while the needles are pulling the loops of a new course through the loops of the last previous course.

Yarn laying means

15

As is usual in a straight knitting machine, yarn is drawn from supply packages or cones, at the rear of the machine, and moved by feeding mechanism to a yarn laying means at the front of the machine, whereby the yarn is fed to the knitting head for formation into loops.

Yarn laying means comprises carrier rods 1-8, inclusive, at the front of the machine, parallel, and adjacent to, the friction rod 23, and longitudinally reciprocably mounted in brackets 120 25 on the center bed 18. Yarn carriers, or guide fingers similar to guide fingers 121, 122 and 124 on the carrier rods 1, 2 and 4, respectively (Fig. 4), are provided on all the rods 1-8 for laying yarn to the needles 32.

The rods 1-8 are connected to, and released from, the friction rod 23 by various friction boxes, only one of which, a box B, necessary to an understanding of the invention, being shown. End stops E, at the ends of the machine, limit the movements of the rods, as will further appear.

Main pattern unit

Pattern mechanism, by which the sequence of operation of various movable elements of the machine is controlled, comprises in this instance, a usual pattern chain at the front of the machine, known as a main pattern unit, because it is the primary source of pattern control, and because there is another pattern unit auxiliary to, 45 and controlled by, the main pattern unit.

A main pattern unit M (Fig. 1) comprises a bracket 127 on the front beam 14, a shaft 128 journaled in the bracket 127, a sprocket wheel or drum device 129 on the shaft 128, and a double 50 chain element 132, acting as one chain, on the sprocket wheel 129. The chain 132 is supported along the front of the machine, on idler rollers (not shown).

The chain is advanced about the sprocket 55 wheels by a ratchet wheel 133, which is operated by a pawl pivotally mounted on the bracket 127, and intermittently actuated by a lever 137 carrying a follower for cooperation with a cam on the cam shaft 22.

A stub shaft 142 is supported in the bracket 127, transversely to the cam shaft 22, and carries a follower 143 disposed between shogging cams 147 and 148 on the cam shaft 22.

A member 149 is fixed at one end to the stub 65 shaft 142, and is slidably supported parallel to the shaft on the bracket 127. A tension spring 152 is connected between the slide member 149 and the stationary bracket 127, and tends to move the stub shaft 142 whereby to move the follower 143 from its normal knitting position, between the shogging cams 147 and 148, to its narrowing position, also between the cams 147 and 148, where it engages other face cam portions of the cams to shog the cam shaft 22. The spring 75

152 is normally prevented from moving the stub shaft by a latch 153, which is released by a button on the chain 132. The stub shaft 142, and the follower 143 thereon, are returned to latched 5 inactive position, against the action of the spring 152, by cooperation between a cam 154 on the cam shaft 22, and a follower 157 on the slide member 149.

A handle lever 158 is pivotally mounted on a 10 shaft 159, and carries a pawl which, by oscillating the handle engages the ratchet wheel 133 to manually advance the chain 132 independently of its power advance when desired. This handle also carries a lever which, when the handle 15 is turned about the shaft 159 to effect the manual adjustment of the chain, is advanced to position which will prevent shogging of the cam shaft 22, by preventing movement of the stub shaft 142 and the follower 143 from inactive to active position if, at this time, a button on the chain 132 should release the latch 153 ordinarily permitting the stub shaft to advance by action of the spring 152.

A plurality of levers G of the main pattern unit 25 M are disposed in side-by-side relation, severally for operation by a button or buttons 162 on the chain 132. Rods R (Fig. 2), including a rod 163 which is the only one thereof necessary to an understanding of the invention, are longitudinally 30 slidably mounted along the front of the machine in bracket bearings secured to the front beam 14. The rods R operate to control various mechanisms of the machine; the rod 163 being actuated by a lever 164 of the levers G to control the operation of an auxiliary pattern unit A (Figs. 1, 2, 6, 7, 11 and 27).

Auxiliary pattern unit

To simplify the construction and operation of 40 the main pattern unit M above set forth, and also to simplify the machine generally and to render it more convenient to control any of various mechanisms from control means closer thereto, the auxiliary control unit A is provided along the 45 rear of the machine. It is operated from the cam shaft 22 and controlled by the main pattern unit M to operate, in a smaller number of steps than the steps or operations of the main pattern unit, which are provided one for each course 50 or partial course formed in the blank being knitted.

The rod 163, above set forth, has fixed thereto 55 a pair of closely adjacent collars 167, spaced a slight distance apart along the rod, between which collars is disposed the lower end of a vertical arm (Fig. 2) of a lever 168. The latter has a horizontal portion, pivotally mounted by a vertical pin 169 on the top of the front beam 14, and a horizontal latch arm portion 172 for movement, 60 when the rod 163 is shifted longitudinally, laterally to a lever 173, between a position directly under an arm 174 of the lever 173 and a position aside the arm 174.

The lever 173 is pivotally mounted on a narrow 65 rowing lift shaft 177, and has an upright arm 178 carrying a roller or follower 179 for cooperation with a cam 182 on the cam shaft 22. A link 183 is pivotally connected, at one end, to the upper end of the arm 178, and at its other end, 70 to a member 184 that is relatively movably mounted on a control or timing shaft 187 of the auxiliary pattern control unit A at the rear of the machine. The shaft 187 extends substantially throughout the length of the machine, and is 75 journaled in bearing brackets 188 fixed to a bar

189 of rectangular cross section that is mounted on the end and center frames 12 and 13, respectively.

The member 184 pivotally carries a pawl 192 for advancing a ratchet wheel 193 fixed to the 5 shaft 187. An idler pawl 194, pivoted on a pin 197 carried by one of the bearing brackets 188, is held by a spring 198 against the ratchet wheel 193 to prevent reverse rotation of the latter. A third pawl 199 (Fig. 1), also pivoted on the pin 10 197, but cooperating with a second ratchet wheel 202, reverse to the ratchet wheel 193 and fixed to the latter, normally tends to prevent advancement of the first ratchet wheel 193. Thus, with the idler pawl 194 locking the ratchet wheel 193 15 against reverse movement, and the pawl 199 locking the ratchet wheel 202 against forward movement, the shaft 187 is positively locked against accidental movement in either direction, from vibration or other cause, and cannot be operated, 20 except when the link 183 is operated by the cam 182, and then only in the forward direction. When this occurs, an arm 203, on the pawl 192, 25 first cooperates with a pin 204 on the pawl 199 to move the latter, against the action of a spring (not shown), to release the ratchet wheel 202 so that, upon continued movement of the pawl 192, the ratchet wheel 193, and consequently, the shaft 187 are advanced by a distance of one notch 30 of the ratchet wheel 193.

The cam 182 is generally of true circular form with the exception of a flat portion 207. The arm 174 of the bell crank 173, is latched by the arm 172, to hold the follower 179 at the high point, or circular part, of the cam 182. A tension 35 spring 208, extending between an extension 209 of the link 183 and a bracket 212 on the back beam 17, biases the follower 179 toward the cam 182, and the arm 174 toward the latch arm 172, so that, when the latch arm is under the arm 40 174, the force of the spring 208 is exerted against the latch arm 172, and the follower 179 is prevented from following the contour of the cam 182. When the latch arm 172 is moved laterally from under the arm 174, the force of the spring 208 45 causes the follower 179 to follow the contour of the cam 182, each revolution of the cam thereby advancing the ratchet wheel 193 one notch.

Along the auxiliary control shaft 187, on 50 sprocket wheels 213 fixed thereto adjacent to corresponding sub-mechanisms of the machine controlled thereby, are pattern means in the form of variable link camming chains, including chains 216, 217, 218 and 219 to be driven by the shaft 187 through the sprocket wheels 213. The chain 55 219 is the only one of the chains 216-219 having links of more than two heights, these links being, as better seen in Fig. 29, high links 224, links 225 of intermediate height, and low links 226. The chain 218 has high links 220 and low links 60 221; the chain 217 has high links 214 and low links 215; and the chain 216 has high links and low links. Sectional or other cam discs may be substituted for the sprocket wheels 213 and the chains, or a combination of chains and discs 65 employed for different mechanisms.

Each of the sprocket wheels 213 and idler sprocket wheels (not shown), which assist in supporting the camming chains, is provided with 70 peripherally spaced transverse grooves 222 for receiving pins 223 connecting the links of the chains 216-219. The periphery of each chain is a cam or pattern device for cooperation with an element or follower, in which the cam device provides for selective variations in its capacity, and 75

the element or follower is retained within a given range and location of movement by the pattern means irrespective of variations in the capacity of the pattern or cam means.

5 *End stop lifting mechanism*

In the knitting of successive equal courses of plain loops, end stops would be required for determining the lengths of the strokes of the carrier rods, but the stops could, in such case, be fixed in position. However, for fashioning the fabric, as in narrowing, wherein the courses are of successively shorter lengths, it is necessary to move the opposite end stops closer together, 10 step by step, and to operate narrowing points in timed relation to the manipulation of the stops. It is also necessary to lift the various end stops, at different times, to allow the corresponding yarn carriers to be moved out of the knitting field, and to control the lifting and lowering of 15 these stops, in accordance with the pattern being knitted.

The stops E, at the ends of the machine, since the operation thereof is not germane to this invention, are, in this instance, illustrated as automatically controlled by the auxiliary pattern control unit A through chains similar to any of the chains 216-219.

Each stop is in the form of a short rod or 20 plunger 227 of rectangular cross section, slidably mounted in a carrier nut 228 on a spindle 230 of a narrowing mechanism, to be herein-after further set forth; the stops being at right angles to the carrier rods 1-8, inclusive, and each 25 having a hook handle, at its upper end. Each plunger is biased downwardly, or toward the corresponding yarn carrier rod by a spring 229 that is connected between the plunger and the carrier nut 228. The plunger, in its latter position, defines one end of the operative, or knitting 30 stroke of the corresponding carrier rod in one direction. When the plunger is lifted, the adjacent end of the corresponding carrier rod travels further toward, and beyond, the stop than during a knitting stroke, to place the 35 corresponding yarn guide finger 123 out of the knitting field.

Narrowing mechanism

In narrowing or fashioning a blank, means are 40 provided whereby straight needle-like loop-manipulating implements, known as points, are arranged in groups to form combs, and are operated to lift loops from certain knitting needles, and to transfer these loops to other knitting 45 needles, either over loops already thereon, or to knitting needles not having loops thereon; these operations being effective to narrow the blank, or to give it other configurations.

A narrowing mechanism at each end of the 50 machine comprises the carrier nuts 228, each mounted on a spindle 230 journaled in bearing blocks 233. Another spindle 234, for controlling point rods 237 and 238, is mounted in bearing blocks 242. The point rods 237 and 238 are longitudinally slidably mounted in brackets 243, carried by a front narrowing shaft 244, parallel to a back narrowing shaft 247, to which it is connected by curved arms 248.

Dipping movements, of the point rods 237 and 55 238, about the axis of the back narrowing shaft 247, are effected by the downward and upward movements of links 249, each pivotally connected, at its upper end, to the front narrowing shaft 244, and, at its lower end, to a lever 252. Each

lever 252 is pivotally mounted on the frame by a pin 253, and carries a roller, or follower 254 for alternate cooperation with circular and contoured cams 257 and 258, respectively, by shogging the cam shaft 22.

In narrowing the blank, after the narrowing points or combs have reached the innermost positions thereof, it is necessary, in resuming narrowing operations on a subsequent blank, to have the combs in proper starting position. This 10 operation is effected by the use of hand cranks 262 and 263 on the spindles 230 and 234, respectively, in a usual manner.

Lifter arms 264, pivotally connected to the end frames 12, as by pins 265, carry followers for co-operation with cams on the cam shaft 22, and are connected, through linkage and pawl and ratchet mechanisms Q, to narrowing nuts 266 in a usual manner.

20 *Carrier rod actuating means*

Since the carrier rods 1-8 operate through strokes of varying lengths, and are generally actuated from a common source, they are driven by a longitudinally reciprocable drive rod, such 25 as the friction rod 23, or its equivalent, which has greater travel than the maximum reciprocation of any of the carrier rods. This action requires connecting means between the carrier rods and the actuator, or friction rod, whereby the yarn 30 carrier rods will be driven to the ends of the strokes thereof, no matter what the distance of the latter, and there released or yieldably held against the action of the actuator while the latter continues its movement to the end of its 35 stroke.

Various means have been provided for this purpose, such as trip release latch mechanisms and the like, but the usual practice is to connect the carrier rods to the friction rod through 40 a friction box which grips the friction rod tightly enough to be positively driven thereby, but may slide relative to the friction rod when the carrier rod hits its stops.

Since friction boxes for connecting single carrier rods are of usual and well known construction, such boxes for the carrier rods hereof are 45 not shown.

The box B, constitutes a part of this invention, for selectively connecting the carrier rods 1, 2 50 and 4 to, and releasing them from, the friction rod 23 in recurrent sequence, in accordance with the "ringless" principle. It also operates to actuate the carrier rod 3 alone, which is not a carrier of the three carrier sequence operation, and to operate the carrier rod 4 alone, which is a carrier of the three carrier sequence.

The box B comprises friction shoes 267, Figs. 15, 16, 19 and 20, carrying leather strips 268 engaging the friction rod 23; pressure on the shoes, 60 and by the latter on the rod 23, being effected to connect the bar to the friction rod by a bowed spring 269, cooperating with the upper shoe 267, through a bracket 272, when a cam 273 is turned, by a shaft 274 on which it is mounted, to the position thereof of Figs. 19 and 20 to depress the arch of the bowed spring 269. As shown in connection with the relaxed position of the spring 269, Fig. 16, the box is released from the friction rod. The shaft 274 (Fig. 28) is journaled in bearing portions 277 of the box B and is connected, through a connector 278, to a sleeve 279 that is pivotally mounted on a shaft 282, and carries a fixed pinion 283. The shaft 282 is mounted in a portion 284 of the box, see also Fig. 75

6, on the upper portion 287 of a pair of split bearing like portions 287 and 288, Figs. 5 and 28, held in position relative to the friction rod 23, as by screws 289, and having bearing liners 5 292.

5 The pinion 283 cooperatively engages a gear wheel 293 slidably splined to a rotatable control shaft 294, by a key 291, Fig. 6; the shaft 294 being longitudinally stationarily journaled, at one 10 end, in a bearing 298, Fig. 22, in a bracket or guide arm 299, secured to a bracket 302 on the back narrowing shaft 247, and, at the other end, in a bearing 303, in a bracket 304 (Fig. 27) fixed to the bar 189. The gear wheel 293 is adapted to 15 move along the shaft 294 with the friction box B, through the cooperation of a fork 307 (Fig. 6) secured to the box and having its prongs in a groove of a collar 309 that is fixed to the gear wheel.

20 A pinion sector 312, as better seen in Fig. 27, on the control shaft 294, is engaged by a gear wheel sector 313, in the nature of a rack, on one arm 314 of a bell crank 317 pivotally mounted, by a pin 318, on the bracket 304. Another arm 319, 25 of the bell crank 317, carries a laterally projecting pin 322 embraced by a forked end 323 of a lever 324 that is pivotally mounted on the bracket 304 by a pin 327, and carries on a pin 326 at its lower end, a roller follower 328 for cooperation with the 30 chain 218, on one of the sprocket wheels 213, on the auxiliary control shaft 187.

25 A spring 329 is connected between one end 332 of the bracket 304 and a hook arm extension 333 of the arm 319 of the bell crank 317, thereby tending 35 to turn the bell crank counter-clockwise about its pivot pin 318, as viewed in Fig. 27, and to turn the lever 324 clockwise about its pivot pin 327, to bias the follower 328 toward the chain 218. A set screw 334, in a lug 335 on the bracket 304, 40 limits the clockwise movement of the lever 324.

40 When the follower 328 engages a low link 221 on the chain 218, the bell crank 317, and the control shaft 294, are in position corresponding to the release position of the spring 269 by the cam 273.

45 A bracket extension 337 of the friction box housing (Fig. 15), has two uprights or arms 338 and 339, between which are disposed lever 342 and 343, rotatably mounted on a shaft 344 that is 50 eccentrically mounted on a smaller shaft 347 (Figs. 15-17); the shafts 344 and 347 being fixed to each other, by a pin 348, in a spacer ring 346, between bushings or sleeves 349 and 350, constituting pivot ends of the levers 342 and 343.

55 Sleeves 352 and 353, mounted on the bushings 349 and 350, are provided with projecting arms 359 and 360, respectively. The levers 342 and 343 further have projecting lugs 354 and 355, respectively, and bracket arms 356 and 357, respectively. Each lug 354 and 355 carries a stop screw 358 for contact with one of the laterally projecting arms 359 and 360 on the sleeves 352 and 353, respectively, each of which arms also has a bracket arm 361, only the arm 361 on sleeve 352 being shown, and lever arms 363 and 364 carrying rollers 367 and 368; a spring 369 extending between the bracket arm 356 and the arm 361 on sleeve 352 biasing the contact screw 358 in the lug 354 and the arm 359 toward each other, and 60 a spring 372 (Fig. 4) extending between the bracket arm 357 and the arm (not shown) on sleeve 353 biasing the lug 355 and the arm 360 toward each other.

65 Another control shaft 371 carries cams 378 and 75 379 (Figs. 15-18) for cooperation with the rollers

367 and 368, respectively, for operating the carrier rods 1, 2 and 4 in three carrier sequence, as will further appear; these cams being parts of sleeves 382 and 383, respectively (Fig. 21), that are splined to the shaft 371 by a key 384 for rotation with, and slideable movement along the shaft. A lever arm 387 has, at its pivot end, a sleeve 388 rotatably surrounding a spacer 389 on the shaft 371, and at its free end, a collar 390 in which is fixed a rod 391 extending oppositely 10 therefrom along the machine. The sleeve 388 has cam portions 392 and 393, also for cooperation with the rollers 367 and 368, respectively.

15 Each selector lever 342 and 343 is biased clockwise about its pivot shaft 344, as viewed in Figs. 15 15, 16, 19 and 20, by a spring 394 extending between a pin 397 on the lever and a pin 398 on the friction box bracket 337. A hook-like bracket 399, fixed to a bar 402 extending along the machine, slideably coats with an outer edge 403 of 20 the friction box bracket 337 to prevent any tendency to lift away from the yarn carrier rods as may be caused by the torsion of certain of the rotatable parts controlling the mechanism of the box.

25 The selector lever 342 further has, at its lower or free end, a pair of fingers 407 and 408 for cooperation, as better seen in Figs. 30-36, inclusive, with dogs 411, 412 and 414 on the carrier rods 1, 2 and 4, respectively, Fig. 36 also showing a dog 413 on the carrier rod 3; the fingers 407 and 408 being selectively shifted, as will further appear transversely to the rods 1-4. The selector lever 343 has similar fingers 417 and 418 for similar cooperation with the rods 1-4. Each 30 dog 411-414 has a body portion of inverted channel section nested over the top edge of the corresponding carrier rods 1-4, and secured to the latter, as by rivets 419 (Fig. 4). The dogs 412, 413 and 414 have plain rectangular block-like 40 upward projections 422, 423 and 424, respectively, for cooperation, through the intermediary of contact screws 427, with the fingers 407, 408, 417 and 418 of the selected levers 342 and 343, and the dog 411 has a projection 421 which, although also 45 corresponding to the aforesaid block-like projections, is further extended laterally or diagonally of its carrier rod 1 to permit further lateral space movement of the selector fingers.

50 Although the dogs 411-414 carry the contact screws 427, as seen in Figs. 2, 3 and 4, which the selector fingers 407, 408, 417 and 418 actually engage, for simplicity of understanding, these screws have been omitted in the sequence diagrams (Figs. 30-36), and the action, to be later 55 herein described, considered as direct engagement of the fingers with the block-like projections 421-424 of the dogs 411-414, respectively.

55 The fingers 407 and 417 of the levers 342 and 343, respectively, since they merely oscillate back and forth laterally of, and between, the yarn carrier rods 1 and 2, are of small width or dimension laterally of the carrier rods, whereas, the fingers 408 and 418 on the levers 342 and 343, respectively, since they similarly oscillate between carrier rods 2 and 4, are of correspondingly greater width laterally of the rods. The levers 342 and 343, as better seen in Figs. 3 and 4, operate with the lever 342 disposed between a wear plate 428 and an integral central portion 429 of the cast bracket 337, and the lever 343 disposed between the portion 429 and a wear plate 432, each of the wear plates 428 and 432 being on the driven side 65 of its associated selector lever.

60 The three carrier selection, or oscillatory 70

movement, of the selector levers 342 and 343, is effected by the cams 378 and 379 (Fig. 18), by mechanism better seen in Figs. 7-14 and Figs. 24-26, in which, also mounted on the shaft 377, 5 to turn the latter, is a ratchet wheel 437 for operation by a pawl 438 that is pivotally connected, by a pin 439, between the arms of a U-shaped portion 440 of a pawl carrier member 442 having ratchet guard flanges 441, and that is 10 pivotally connected, by a pin 443, to one end of a link 444. This link has its other end connected, by a pin 447, to one arm 448 of a lever 449 pivotally mounted on the back narrowing shaft 247 and having another arm 452 carrying a stop 15 screw 453 for cooperation with a bar 454. The arm 448 carries a roller follower 457 for cams 458 (Fig. 25) on a bracket or bar 462 carried by the slur cam boxes 92. A spring 463, extending between a pin 464 on the pawl 438 and a pin 465 20 on the member 442, biases the pawl toward the ratchet wheel 437. The stop screw 453 prevents the follower 457 from dropping into a space between the cams 458. At each stroke of the slur cam boxes 92, the follower 457 is raised to advance the ratchet wheel 437 one notch. A spring 466, connected between a pin 467 and a clamp bracket 468 (Fig. 3), biases the follower 457 toward the cams 458.

During the operation of the yarn carrier rods 30 1, 2 and 4, the follower 457 is thus raised, and lowered, during each stroke, to raise the link 444 to actuate the pawl 438. This action turns the ratchet wheel 437 to rotate the cams 378 and 379 against the rollers 367 and 368, respectively, 35 whereby to impart the three-carrier oscillating action to the selector levers 342 and 343.

In order to prevent misalignment of the dogs 411-414 relative to the selector levers 342 and 343, resulting from rebound of the carrier rods 40 from the end stops E, there are provided rebound preventing devices 469, portions of which, indicating the positions thereof on the carrier nuts 228, are shown in Fig. 1, and the detail structure of one of which is shown in Figs. 12 and 13. 45 Each device 469 comprises a housing 470 enclosing detents 471, 472 and 474 in the form of plunger rods biased downwardly by springs 479, and having tapered lower ends for cooperation with notches 480 in dogs on the rods 1, 2 and 4, 50 respectively, such as the dog 482 on the rod 2. A main lower cylindrical body portion of each plunger slidably fits a bore in the housing 470 and has an upper portion of smaller diameter around which the corresponding spring 479 is 55 disposed, and on a top screw threaded portion of which nuts 485 are provided to limit the downward movement thereof. A pin 487, on each plunger, is disposed in a slot 488 in the housing 470 to prevent turning of the plunger, and to 60 hold it in proper position relative to its notch 480. The dog 482, and the other dogs for the rods 1 and 4, are similar to the dogs 411, 412 and 414 in that they each are of inverted channel section fitted over the top edge of the corresponding 65 carrier rod and secured thereto, as by rivets 489. The housing 472 is secured to the carrier nut 228 by screws 492.

In Fig. 19, the parts are shown as positioned during one phase of the three-carrier or sequential carrier operation, the cams 392 and 393 being in such positions as not to interfere with the free oscillation, of the selector levers 342 and 343 by the cams 378 and 379, back and forth relative to the carrier rods 1, 2 and 4, as above generally indicated. When it is desired to operate only one

of the sequential carrier rods 1, 2 and 4, in this case the carrier rod 4, it is only necessary to stop the rotation of the shaft 377 in such position that the cams 378 and 379 will stop the oscillation of the fingers 408 and 418 at positions opposite the dog 414 on the rod 4. This stopping of the rotation of the shaft 377 is attained by one of the links 225 of intermediate height in the chain 219. 5

In Fig. 20, the parts are shown as positioned 10 during the operation of a single carrier rod, which is not a rod of the three-carrier or sequential sequence, in this case, the carrier rod 3, it being noted that the cams 392 and 393 are raised, from the positions of Fig. 19 to the positions of 15 Fig. 20, against the rollers 367 and 368, to hold the selector levers 342 and 343 in position, with the fingers 407 and 417 opposite the dog 413.

Both of the features, set forth relative to Figs. 19 and 20, are controlled by mechanisms, better 20 shown in Figs. 7-11, in which a bracket 491, on the bar 189, supports a pivot pin 498 on which is mounted a lever 499 carrying, on a pin 496, a roller follower 502 for the chain 219, and connected, through a lost motion connection 503, to 25 a rod 504. Nuts 507, spaced from nuts 508 on the rod 504, determine the limits of the lost motion, or movement of the rod 504 through a member 509 having a portion 512 pivotally mounting the member on the lever 499. A spring 30 500, connected between a hook portion 501, on the lever 499, and a stationary part of the machine frame, biases the follower 502 toward the chain 219. The rod 504 is connected, at its upper end, to an arm 513 of a lever 514 that is 35 pivotally mounted on the back narrowing shaft 247. A spring 510, connected between the arm 513, by a pin 511, and a clamp bracket 515 on the shaft 103, biases the lever 514 clockwise, as viewed in Fig. 11, which movement is limited by 40 contact of a screw 516 in an arm 521 of the lever 514 with the bar 189. A latch element 517 is also pivoted on the pin 498 and connected to the lever 499 by a spring 518, between a hook 519 on the element 517 and a pin 522 on the lever 499. 45 A set screw 520, positioned on the element 517, beneath the lever 499, limits movement of the element relative to the lever 499, in one direction. The latch element 517 is adapted to engage, and catch, an arm 523, constituting a third arm of 50 the lever 449, whereby to hold the follower 457 at the high points of the cams 458, and to thereby stop the sequence of carrier selecting oscillation of the selector levers 342 and 343, and to retain a connection between the friction box B and the 55 carrier rod 4, by lifting and holding the follower 457 off the cams 458, as above described as being effected by a link 225 of the intermediate height on the chain 219. When the follower 502 is moved farther, by a high link 224 on the chain 60 219, the lever 499 takes up the lost motion of the connection 503 and actuates the lever 514 to move the arm 513 thereof counterclockwise about the shaft 247, from its position of Fig. 7 to its position of Fig. 11. 65

A free end portion 524 of an arm 527 of the lever 514 has a slot 528, and a lateral projection 529 (Fig. 3), which, while the device is operating the carrier rods 1, 2 and 4 in recurrent sequence, are in position to receive one end of the rod 391 70 in an idle action at the corresponding end of each double stroke of the friction box. However, when it is desired to discontinue the action of the device as a sequential or three-yarn carrier, and to have the box B operate only one of the 75

carrier rods, and in this instance, to have this one rod other than one of the three-sequence carriers 1, 2 and 4, such as the rod 3, when the rod 391 is laterally opposite the projection 528 at the time the arm 527 is moved counterclockwise, from its position of Fig. 7 to its position of Fig. 11, the lever arm 387, and consequently the cam 392, will be moved from the positions of Fig. 19 to the positions of Fig. 20, as above pointed out.

During the latter operation, the double pointed rod 391 not only moves into and out of the slot 528, at one end of its stroke, but also, at the other end of its stroke, moves into and out of a socket 532 (see Fig. 26) at the free end of one arm 533 of a bracket 534, surrounding the control shaft 377, and having an arm 537 fixed to the stationary bar 402. In entering the slot 528 and the socket 532, the rod 391 receives a camming or centering action to maintain it, and its associated parts, in proper position against slight jarring displacements.

The shaft 377 is damped against such displacements, and the cams 378 and 379 are accurately accentuated in proper camming positions, by a damping device N, Figs. 3, 22 and 23, comprising a body portion 542 of disc-like character having a lower split bearing portion 543 around a sleeve 541 embracing the friction rod 23, and an upwardly projecting tubular portion 544. The body 542 is held relative to the shaft 377, at one side of the body, by a collar 545 and a pin 546 extending through the collar and the shaft 377. A metal disc 547, has peripheral lugs 548 forming slots therebetween, in which stationary dogs 549 of the body 542 are disposed to prevent turning of the disc 547. The disc 547 is biased away from the body 542 by helical springs 552 disposed in recesses in the body 542, the disc thus being biased against a friction disc 553, as of leather, on a sleeve member 554. Nuts 557 hold the sleeve 554 in adjusted position on the shaft 377 relative to the friction disc 553. The sleeve 554 has a notched peripheral portion 558 for cooperation with a detent plunger 559 in the tubular projection 544, the plunger being biased toward the notched peripheral portion 558, by a spring 562 extending between a side pin 563 on the plunger and a hook portion 564 on the body portion 542. The notches in the periphery of the portion 558 are peripherally spaced from each other in accordance with the camming positions of the cams 378 and 379, whereby the movement of the latter is accurately dampedly controlled against accidental displacement, and the cams always stop on exact camming positions. A lug 567, on the split bearing portion 543, supports a screw 568 for impingement against the bar 454, and a lug 569, on the body portion 542, supports a screw 572 for impingement against a boss 573 on the bracket 302, thus to lock the device N against turning in either direction about the friction rod 23.

Referring to Figs. 3, 4, 6, 15, 16, 17 and 22, a mechanism, for throwing the selector levers 342 and 343 completely out of operation, either for single carrier, or multiple carrier operation, comprises crank arms 571 and 578, fixed to the small shaft 347, and having side projecting pins 582 and 583, respectively. The pin 582 is disposed in a slot 584 at one end of a lever 587 having a pivot boss 588 pivotally mounting the lever on a pin 589 fixed to the arm 338 of the friction box bracket 331. The other end of the lever 587 has a sleeve 592, in which is fixed a double-pointed

rod 593, similar to the rod 391, but longer. The rod 593 is likewise disposed in a sleeve 594, at the upper end of a lever 597, similar to the lever 587, having a pivot boss 598 connected, by a pin 599, to the bracket 339, and having a lower slotted arm 602 related to the pin 583 the same as the slot 584 is related to the pin 582. A spring 603, extending between the pin 583 and a pin 604 on the lever 597, biases the pins 582 and 583 toward the tops of their slots in the levers 587 and 597, respectively.

The rod 593 is reciprocated, by the friction box B, such that, at one end of its stroke, the rod enters a centering socket 607 on the guide arm 299, similarly to the manner in which the rod 391 enters the socket 532, and, at the other end of its stroke, enters a flattened tube-like socket 608 at the upper end of one arm 609 of a lever 612 that is pivotally connected to the back narrowing shaft 247 and has other arms 613 and 614. The arm 614 carries a contact screw 617 for limiting movement of the lever 612 by engagement of the screw 617 with the bar 189. The arm 613 is pivotally connected, at its free end, by a pin 618, to the upper end of a link 619 that is pivotally connected, at its lower end, by a pin 622, and nuts 621, to a lever 623. The latter is pivotally connected, by a pin 624, to a bracket 627 on the bar 189 and rotatably carries, on a pin 628, a roller follower 629 which is biased against the chain 217 by a spring 632 connected between a hook portion 637 on the lever 623 and a bracket 630 on the back beam 17.

With the follower 629 on a low link of the chain 217, the parts are positioned as in Fig. 15, with the selector arms 342 and 343 in position for active cooperation with the carrier rod dogs 421-424 either in the three-carrier sequence above mentioned, or the single-carrier operation set forth.

However, when a high link of the chain 217 engages the follower 629, the lever 623 is moved counterclockwise about the axis of the pin 624, as viewed in Fig. 15, against the action of the spring 632, to raise the arm 613 of the lever 612. This action turns the lever 612 counterclockwise about the back narrowing shaft 247, as viewed in Fig. 15, whereupon the levers 587 and 597 are turned counterclockwise about their pivot pins 589 and 599, respectively, which action effects a counterclockwise turning of the shaft 347, through the pins 582 and 583, and the crank arms 577 and 578.

Turning of the shaft 347, as aforesaid, eccentrically turns the shaft 344 from its position of Fig. 15, in which the selector levers 342 and 343 are in active positions relative to the carrier rods 1-4, to the position of Fig. 16, in which the selector levers 342 and 343 are lifted entirely free from the carrier rod dogs or contact screws with which they normally cooperate.

This action is so synchronously timed with the action of the mechanism of Fig. 27 that, simultaneously with the lifting of the selector levers 342 and 343 from the positions thereof of Fig. 15 to the positions thereof of Fig. 16, the friction box B is released from the friction rod 23. Conversely, when, by the reversal of the above-described movements, the selector levers 342 and 343 are moved back from the inactive positions thereof relative to the carrier rods, as seen in Fig. 16, to the active positions of these levers relative to the rods, as seen in Fig. 15, the mechanism of Fig. 27 is actuated to simultaneously

close the friction box B in operative connection to the friction rod 23.

Since this action takes place at the right hand end of the friction box stroke, a further feature 5 of operation, not heretofore mentioned, resides in the locking of the friction box B, when it is open and detached from the friction rod 23, by a yoke 642 (Figs. 3 and 4) on the shaft 294, which embraces a lug 643 on the box B for this purpose. 10 Further, a collar 644, secured to the control shaft 377, as by a pin or screw 645, acts as a stop for the friction box B when the latter is moved outside its range of yarn laying movement.

Shock absorber

Formerly, when straight or full fashioned knitting machines were operated at what are now considered relatively slow speeds, the carrier rods did not engage the stops with sufficient force 20 to cause any noticeable detrimental effects, but, with the introduction of the higher more modern speeds, the shocks of impact of the carrier rods with the stops became so great as to render the reduction of these shocks highly desirable.

Mechanism, for absorbing the shocks of impact 25 of the carrier rod 3 when laying a single yarn in the welt of a stocking and of the carrier rods 1, 2 and 4 when operating in sequence in the "ringless" areas of the blank, and for automatically throwing the shock absorber into and out of 30 operation, is shown in the above-mentioned Patent No. 2,101,048 to Alfred E. Ischinger, and only so much thereof as is necessary to an understanding of the present mechanism is shown 35 herein.

It comprises a rod 647 which extends parallel to the friction rod 23 and is longitudinally reciprocated in sub-synchronism therewith by a link connection (not shown) to the usual pitman 40 of the coulier motion mechanism of the machine whereby, although it travels at the same time and in the same direction as the friction rod at each stroke of the latter, its speed and distance 45 of travel of the friction rod. Half speed, of the shock absorber rod 647 relative to the speed of the friction rod, has been found an effective speed, although the aforesaid link is capable of adjustment to vary the speed of the shock absorber rod 50 over a wide range.

The half speed rod 647 carries collars 648 in the nature of split rings or clamps held in position around the rod 647 by screws 649, to intercept a lever 652 that is hinged, by a pin 653 (Figs. 4 and 5), to the friction box B; the action being such that, with the lever 652 in active position for intercepting the collars 648, as the friction box approaches the end of each stroke, the arm 652 intercepts one of the collars 648. From the time 60 of such interception to the end of the stroke, the friction box is partially carried by the friction rod 23 and partially slips relative thereto such as to travel, not at the speed of the friction rod, but at the speed of the rod 647. Thus, the carrier rod, attached to the friction box at the time, 65 strikes its end stop with considerably less force of impact than it would if allowed to travel its entire distance at the speed of the friction rod. A spring biased ball detent 654, indicated in Fig. 70 5, cooperates with a notch in the lever 652 to hold the latter in position.

To automatically throw the lever 652 from its active position relative to the collars 648, as shown in Fig. 15, for instance, to its inactive 75 position relative to these collars, as shown in Fig.

16, which occurs when the selector levers 342 and 343 are thrown to inactive position, as indicated also in Fig. 16, and when the friction box B is released from the friction rod 23, jaws 657 (Fig. 1) are provided on a lever 658, see also Fig. 5. These jaws extend lengthwise of the machine, and have tapered ends 659 adapted to readily lead a cooperatively tapered portion 662 of the lever 652 to position between the jaws.

The lever 658 is pivotally mounted, by a pin 10 663, on a bracket 664 on the bar 189, and has a lever arm 667 on which a roller follower 668, journaled by a pin 669, is rotatably mounted for camming cooperation with the chain 216. A spring 672 connected between a hook portion 673 15 and an arm 674 of the bracket 664, the actual connection not being shown, biases the follower 668 toward the chain 216; this movement being limited by a set screw 677 which is disposed in a lug 678 on the bracket 664, and engages the 20 lever 658.

With the machine, and the operation of its individual mechanisms understood as above set forth, the general operation of the machine in producing the blank of Fig. 29, is as follows: 25

Operation

Referring particularly to Figs. 29-36, after one stocking blank, of the type shown in Fig. 29, has been completed on each knitting section, which 30 may be of any desired number, and prior to the start of a next blank or blanks, the auxiliary pattern control chains operate through a distance represented between lines V and X (Fig. 29) to idly reposition the various parts of the 35 machine, at which time the chain 217 operates, by causing its follower 629 to ride from a high link 214 to a low link 215, to lower the selector levers 342 and 343 from the inactive position of Fig. 16 to the active position of Fig. 15 relative 40 to the yarn carrier rods 1-4. At the same time, the auxiliary pattern control chain 219 operates, by causing its follower 502 to ride from a link 225 of intermediate height to a high link 224, to cause the fingers 407 and 417 of the selector 45 levers 342 and 343, respectively, to assume a position, as indicated in Figs. 20 and 36, for operating the carrier rod 3 alone. Also, at the same time, the auxiliary pattern control chain 218 operates, by causing its follower 328 to ride from a 50 low link 221 to a high link 220, to operatively connect the friction box B to the friction rod 23, by action of the gear wheel sector or rack 313 (Fig. 27) against the pinion sector 312; it being noted that, upon the latter action, including the turning of the shaft 294, the yoke 642, which had been holding the friction box B against movement with the friction rod 23, by locking engagement with the lug 643 on the friction box frame, is released from the lug 643 to permit reciprocation of the friction box B with the friction 55 rod 23.

As above conditioned, a carrier finger of the 60 yarn carrier rod 3 lays a yarn to form a welt W of the blank of Fig. 29 to a course Y, several 65 courses beyond a welt line S, after the welt W has been turned.

At the course Y, the auxiliary pattern control chain 218 operates, by causing its follower 328 to ride from a high link 220 to a low link 221, to 70 disconnect the friction box B from the friction rod 23, by action of the gear wheel sector 313 on the pinion sector 312, and another friction box (not shown) caused to operate one of the carrier rods, such as the rod 6, to lay a yarn forming an 75

identifying stripe for any selected number of courses from the course Y to a course T; this yarn being of ingrain yarn, or the like, and dyed or otherwise constituted to form a contrast with 5 adjoining areas.

As the identifying stripe carrier is removed from the knitting field, the friction box B is again operatively connected to the friction rod 23, when the follower 328 rides from a low link 10 221 to a high link 220 of the auxiliary pattern chain 218, whereby the gear wheel sector 313 acts on the pinion sector 312. At the same time, the auxiliary pattern control chain 219 causes its follower 502 to ride from a high link 224 to a 15 low link 226 to condition the parts, as in Fig. 19, for sequential operation of the carrier rods 1, 2 and 4, through the operation of the cam 457 (Fig. 25) by the cams 458 and the resultant advancement of the control shaft 377 (Fig. 11) by the 20 pawl 438.

From the course T, to an instep course J, the carrier rods 1, 2 and 4 are operated in recurrent sequence, as explained below in connection with Figs. 30-35, this operation being carried on at 25 high speed, except at a narrowing area K, in the knee region, and a narrowing area Z in the lower region of the leg L of the blank, and through reinforced heel areas H, where the speed is reduced. In the areas K and Z, the yarns are laid at high 30 speed, but the machine speed is reduced during the narrowing operations.

Referring to Fig. 30, the finger 418 of the selector lever 343 is behind the dog projection 424 on the carrier rod 4, ready to move this rod to 35 the left; the finger 408 of the selector lever 342, at this time, being at the leading side of the dog projection 424, and the finger 417 of the lever 343 being in line with the dog projection 422 of the carrier rod 2.

40 As indicated in Fig. 31, the carrier rod 4 has been moved to the left, against its stop E, and the selector lever 342 shifted laterally of the carrier rods, as above set forth, to a position in which its finger 408 is behind the dog projection 422 on the carrier rod 2. During the latter action, the finger 417, which had moved along its stroke in line with the dog projection 422, is now against this projection, thereby acting as a holding lever, while the selector lever 342 is shifted 45 to place its finger 408 behind the dog projection 422 for the next stroke of the carrier rod 2 to the right. This action, of the differential, or non-simultaneous shifting of the selector levers 342 and 343, although it accomplishes the same general result of a single finger shifting between 50 slots in the respective carrier dogs, has the aforementioned holding action of one lever on one carrier while the other lever is being shifted; this action being carried on throughout the sequence 55 at each release of one carrier and connection to another.

As indicated in Fig. 32, the carrier rod 2 has been moved against its right end stop E, and the selector lever 343 has been moved laterally of the 60 rods to a position in which its finger 417 is behind the dog projection 421 to move the rod 1 to the left; the finger 407 of the selector lever 342, at this time being at the leading side of the dog projection 421 of the rod 1, and the finger 418 65 of the lever 343 being in line with the dog projection 424 on the rod 4.

As indicated in Fig. 33, the carrier rod 1 has been moved against its left end stop E, and the selector lever 342 has been moved to a position 70 in which its finger 408 is behind the dog projec- 75

tion 424 to move the rod 4 to the right; the finger 418 of the selector lever 343, at this time, being at the leading side of the dog 424 of the rod 4, and the finger 407 of the rod 342 being in line with the dog projection 422 on the rod 2. 5

As indicated in Fig. 34, the carrier rod 4 has been moved against its right end stop E, and the selector lever 343 has been moved to a position in which its finger 418 is behind the dog projection 422 to move the rod 2 to the left; the finger 407 of the lever 342 being at the leading side of the dog projection 422, and the finger 417 of the lever 343 being in line with the dog projection 421 on the rod 1. 10

As indicated in Fig. 35, the carrier rod 2 has been moved against its left end stop E, and the selector lever 342 has been moved to a position in which its finger 407 is behind the dog projection 421 to move the rod 1 to the right, to its position of Fig. 30; the finger 417 of the lever 343 being 20 at the leading side of the dog projection 421, and the finger 408 of the lever 342 being in line with the dog projection 424 on the rod 4. 15

The next step would be the same as that occurring from Fig. 35 to Fig. 30 completing a full cycle of the three-carrier operation of the carriers 1, 2 and 4, in which each carrier is carried through a complete double stroke cycle. 25

At the instep course J, the auxiliary control 30 chain 219 moves its follower 502 from a low link to a link of intermediate height whereby to hold the selector levers 342 and 343 in the positions of Figs. 15, 19 and 30 wherein the fingers 408 and 418 of these levers, respectively, embrace the projection 424 on the dog 414 of the carrier rod 4 35 to operate the latter alone, and in successive courses, through a ravel area U; the reinforced areas H having been started and continued, as by the introduction of the carrier fingers of rods 7 and 8, in a usual manner not particularly a part 40 of this invention.

After completing the instep ravel area U, the friction box B removes the carrier of the rod 4 from the knitting field, during an idle course movement, also during which the carriers laying 45 yarn to the right heel tab area, shown at the left of Fig. 29, are moved out of the knitting field, with the rod 4.

Next, the auxiliary pattern control chain 217 50 moves its follower 629 from a low link 215 to a high link 214, whereby to raise the selector levers from active relation to the carrier rods to the inactive position of Fig. 16, and the auxiliary pattern control chain 218 moves its follower 328, 55 from a high link 220 to a low link 221, to disconnect the friction box B from the friction rod 23. After this operation, the right heel tab carriers are brought back into the knitting field, and the heel tabs are completed in a usual manner. 60

Modification

In the modification of the invention, illustrated in Figs. 37 and 38, parts, corresponding to parts shown in previous figures, are designated by corresponding reference characters each having the 65 suffix *a*.

In this form, the above-described structure whereby the friction box B is attached to, and released from, the friction rod 23 by one mechanism including the auxiliary control chain 218, 70 and the selector levers 342 and 343 are moved between active and inactive positions by another mechanism, including the pattern chain 217, the corresponding features are combined in one 75 mechanism and operated by a single auxiliary 75

pattern control chain 684; a chain 216a, and its associated mechanism, corresponding to the chain 216, and its mechanism, and a chain 219a, and its associated mechanism, corresponding to 5 the chain 219, and its mechanism, above set forth, being retained in the modification.

Referring to Figs. 37 and 38, and particularly comparing Fig. 38 with Figs. 6 and 27, the lever 609 and associated parts, including the chain 10 217, are entirely eliminated. A pinion sector 312a, similar to the sector 312, is provided for cooperation with the gear wheel sector or rack 313a, corresponding to the sector 313.

Thus, instead of the two chains 217 and 218, 15 the one chain 684 is provided to operate both the connecting and disconnecting means of the friction box Ba relative to the friction rod 23a, and to operate the selector levers 342a and 343a between active and inactive positions.

20 In the positions of the parts shown, the friction box Ba is operatively connected to the friction rod 23a, and the selector levers 342a and 343a are in active positions relative to the yarn carrier rods 1, 2 and 4, the follower 328a being 25 on a high link of the chain 684 which has high links 692 and low links (not shown).

When operation of the chain 684 causes the follower 328a to ride from one of the high links 30 692 to one of the above-mentioned low links, then a lever 324a, corresponding to the lever 324, is turned clockwise about a pivot pin 327a, as viewed in Fig. 38, which action is transmitted, through a fork 323a and a lever 311a, to a gear wheel sector or rack 313a. This movement of the 35 latter is transmitted to the pinion sector 312a, to turn a shaft 294a clockwise, as viewed in Fig. 38, whereby to turn a gear wheel 293a and a pinion 283a, and operate a cam (not shown), corresponding to the cam 273 (Fig. 28); this action 40 operating to open the friction box Ba, or release it from the friction rod 23a.

At the same time, motion of the gear wheel 45 293a is transmitted, through an idler pinion 688, to a pinion 689 on the small shaft 347a, to turn the latter in an operation similar to that above described wherein parts corresponding to those of Fig. 15 are moved to positions corresponding to the positions of the parts shown in Fig. 16, to move the selector levers 342a and 343a from 50 active to inactive positions, the same as the levers 342 and 343 are moved between the positions of Fig. 15 to the positions of Fig. 16.

Of course, the improvements specifically 55 shown and described by which I obtain the above results, can be changed and modified in various ways without departing from the invention herein disclosed and hereinafter claimed.

I claim:

60 1. In a knitting machine, a plurality of yarn carriers, carrier actuating and control mechanism comprising a friction rod, a friction box, and means including a pair of selector members carried by the box for operatively connecting each of at least three of said carriers to, and releasing them from, the box in recurrent sequence, and means responsive to operation of the machine for unitedly moving said pair of selector members between active and inactive positions.

65 2. In a knitting machine, a plurality of yarn carriers, carrier actuating and control mechanism comprising a friction rod, a friction box, and means carried by the box for operatively connecting at least three of said carriers to, and releasing them from, the box in recurrent se-

quence, means responsive to operation of the machine affecting said mechanism to actuate carriers between said sequential and other operation, and means responsive to operation of the machine for moving said connecting and releasing means between active and inactive positions. 5

3. In a knitting machine, a plurality of yarn carriers, carrier actuating and control mechanism comprising a friction rod, a friction box, and means including a pair of selector members 10 carried by the box for operatively connecting at least three of said carriers to, and releasing them from, the box in recurrent sequence, means responsive to operation of the machine for unitedly moving said pair of selector members between 15 active and inactive positions relative to the carriers, and means responsive to operation of the machine for connecting the box to, and releasing it from, the friction rod.

4. In a knitting machine, a plurality of yarn carriers, carrier actuating and control mechanism comprising a friction rod, a friction box, and means carried by the box for operatively connecting at least three of said carriers to, and releasing them from, the box in recurrent sequence, means responsive to operation of the machine affecting said mechanism to actuate carriers between said sequential and other operation, means responsive to operation of the machine for moving said connecting and releasing 30 means between active and inactive positions relative to the carriers, and means responsive to operation of the machine for connecting the box to, and releasing it from, the friction rod. 35

5. In a knitting machine, a plurality of yarn carriers, carrier actuating and control mechanism comprising a friction rod, a friction box, and means carried by the box for operatively connecting at least three of said carriers to, and releasing them from, the box in recurrent sequence, means affecting said mechanism to actuate carriers between said sequential and other operation, and means responsive to operation of the machine for moving said connecting and releasing means between active and inactive 40 positions. 45

6. In a knitting machine, a plurality of yarn carriers, carrier actuating and control mechanism comprising a friction rod, a friction box, and means comprising a plurality of driving 50 members carried by the box for operatively connecting at least three of said carriers to, and releasing them from, the box in recurrent sequence, means for unitedly moving said connecting and releasing means between active and 55 inactive positions relative to the carriers, and means responsive to operation of the machine for connecting the box to, and releasing it from, the friction rod.

7. In a knitting machine, a plurality of yarn carriers, carrier actuating and control mechanism comprising a friction rod, a friction box, and means carried by the box for operatively connecting at least three of said carriers to, and releasing them from, the box in recurrent sequence, 65 means affecting said mechanism to actuate carriers between said sequential and other operation, means responsive to operation of the machine for moving said connecting and releasing means between active and inactive positions relative to 70 the carriers, and means responsive to operation of the machine for connecting the box to, and releasing it from, the friction rod.

8. In a knitting machine, a plurality of yarn carriers, carrier actuating and control mecha- 75

nism comprising a friction rod, a friction box, and means carried by the box for operatively connecting at least three of said carriers to, and releasing them from, the box in recurrent sequence, means responsive to operation of the machine affecting said mechanism to actuate carriers between said sequential and other operation, means for moving said connecting and releasing means between active and inactive positions relative to the carriers, and means responsive to operation of the machine for connecting the box to, and releasing it from, the friction rod.

9. In a knitting machine, a plurality of yarn carriers, carrier actuating and control mechanism comprising a friction rod, a friction box, and means carried by the box for operatively connecting at least three of said carriers to, and releasing them from, the box in recurrent sequence, means affecting said mechanism to actuate carriers between said sequential and other operation, means for moving said connecting and releasing means between active and inactive positions relative to the carriers, and means responsive to operation of the machine for connecting the box to, and releasing it from, the friction rod.

10. In a knitting machine, a plurality of yarn carriers, carrier actuating and control mechanism comprising a friction rod, a friction box, and means carried by the box including an eccentric device and carrier selector elements mounted on the eccentric device for operatively connecting the carriers to, and releasing them from, the box, and means responsive to operation of the machine for actuating said eccentric device to move said selector elements between active and inactive positions relative to the carriers.

11. In a knitting machine, a plurality of yarn carriers, carrier actuating and control mechanism comprising a friction rod, a friction box, and means carried by the box including a plurality of elements movable relative to the box for connecting each of the carriers to, and releasing the same from, the box, said elements moving relative to each other in moving from each carrier to another, and means responsive to operation of the machine for unitedly moving said connecting and releasing elements between active and inactive positions relative to the carriers.

12. In a knitting machine, a plurality of yarn carriers, carrier actuating and control mechanism comprising a friction rod, a friction box, and means carried by the box including a plurality of elements movable relative to the box for connecting the carriers to, and releasing the same from, the box, said elements being movable relative to each other in moving from each carrier to another, means for unitedly moving said elements between active and inactive positions relative to the carriers, and means responsive to operation of the machine for connecting the box to, and releasing it from, the friction rod.

13. In a knitting machine, a plurality of yarn carriers, carrier actuating and control mechanism comprising a friction rod, a friction box, and means carried by the box for operatively connecting certain of said carriers to, and releasing them from, the box in recurrent sequence, means responsive to operation of the machine affecting said mechanism to actuate carriers between said sequential carrier operation and operation of a carrier other than a carrier of said sequence, and means responsive to operation of the machine for moving said connecting and releasing means be-

tween active and inactive positions relative to the carriers.

14. In a knitting machine, a plurality of yarn carriers, carrier actuating and control mechanism comprising a friction rod, a friction box, and means carried by the box for operatively connecting certain of said carriers to, and releasing them from, the box in recurrent sequence, means responsive to operation of the machine for changing the operation of said mechanism between said sequential carrier operation and repeated single yarn laying operation by a carrier of the sequence, means responsive to operation of the machine for changing the operation of said mechanism between said sequential carrier operation and operation of a carrier other than a carrier of said sequence, and means responsive to operation of the machine for moving said connecting and releasing means between active and inactive positions.

15. In a knitting machine, a plurality of yarn carriers, carrier actuating and control mechanism comprising a friction rod, a friction box, and means comprising a plurality of driving members for operatively connecting at least three of the carriers to, and releasing them from, the box in recurrent sequence, and a single means including a gear element responsive to operation of the machine for unitedly moving said connecting and releasing means between active and inactive positions relative to the carriers and for connecting the box to, and releasing it from, the friction rod.

16. In a knitting machine, in combination with three carriers, two positioned at one end of the machine and one positioned at the other end of the machine, means comprising a plurality of driving members operated by a power element of the knitting machine for successively operating said three carriers, one at a time for travel of a single course only, and then repeating such cycle of operation, and means responsive to operation of the machine for unitedly moving said carrier operating means between active and inactive positions.

17. In a knitting machine, in combination with three carriers, a pair of said carriers being initially positioned at one selvedge edge of the stocking being knitted and the remaining single carrier being positioned at the other selvedge edge of the stocking, and mechanism comprising a plurality of driving members operated by a power member of the knitting machine for first engaging and moving one of said pair of carriers a single course distance, then engaging said single carrier and moving the same a single course distance, then engaging the remaining carrier of said pair and moving the same a single course distance, and repeating such cycle of operation of the carriers, and means responsive to operation of the machine for unitedly moving said mechanism between active and inactive positions.

18. In a knitting machine, in combination with three carriers, a friction rod, a friction box, a pair of said carriers being initially positioned at one selvedge edge of the stocking being knitted and the remaining single carrier being positioned at the other selvedge edge of the stocking, and mechanism including a pair of selector members associated with said friction box operated by a power member of the knitting machine for first engaging and moving one of said pair of carriers a single course distance, then engaging said single carrier and moving the same a single course distance, then engaging

the remaining carrier of said pair and moving the same a single course distance, and repeating such cycle of operation of the carriers, and single unitary means responsive to operation of the machine for unitedly moving said selector members between active and inactive positions relative to the carriers and for connecting the box to, and releasing it from, the friction rod.

19. In a knitting machine, a plurality of yarn carriers, carrier actuating and control mechanism comprising a friction rod, a friction box,

and means carried by the box including an eccentric device and carrier selector elements mounted on the eccentric device for operatively connecting the carriers to, and releasing them from, the box, and a single unitary means responsive to operation of the machine for actuating said eccentric device to move said selector elements between active and inactive positions relative to the carriers and for connecting the box to, and releasing it from, the friction rod.
